UNITED STATES PATENT OFFICE.

DONALD S. BARROWS, OF PATERSON, NEW JERSEY, ASSIGNOR TO AMERICAN CAR AND FOUNDRY COMPANY, OF ST. LOUIS, MISSOURI, A CORPORATION OF NEW JERSEY.

DOOR-OPERATING DEVICE.

1,078,241.

Specification of Letters Patent. Patented Nov. 11, 1913.

Application filed July 6, 1911. Serial No. 637,205.

To all whom it may concern:

Be it known that I, DONALD S. BARROWS, residing at Paterson, Passaic county, New Jersey, and being a citizen of the United States, have invented certain new and useful Improvements in Door-Operating Devices, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a transverse vertical view through approximately one-half of a car underframe illustrating a discharge door in the floor thereof, and the mechanism comprising this invention applied thereto for operating said door. Fig. 2 is a vertical detail section view illustrating the manner in which doors disposed upon opposite sides of one of the cross bearers of the underframe are connected and operated by the elements comprising the invention. Fig. 3 is a detail sectional view illustrating a modification.

The object of this invention is to provide a simple, efficient and positive means for operating the discharge doors in the floors of railway cars.

A further object is to arrange the door operating mechanism in such manner as to be entirely protected from all possible injury when the doors are opened and the material of the lading is being dumped.

It will be understood that there may be any desired number of doors throughout the length of the car, and upon opposite sides of the median line thereof, as illustrated in the drawings or disposed to swing upon hinges arranged transversely of the car as may be desired, and that each of said doors is pivotally supported by the frame work of the car, all of which is common in the construction of cars to which this invention is applicable. It will also be understood that the elements comprising this invention, when used in cars having longitudinally disposed doors, are duplicated, at each of

the cross bearers and upon opposite sides of the center sills.

Referring to the drawings, 1 indicates one of the center sills, 2 one of the side sills, and 3 one of the cross bearers, all of which are well known as rigid members of the car structure. The door 4 is pivotally mounted in a suitable bracket 5 fixed as shown to one of the center sills 1 and extends from said center sill toward the outer side of the car and underlaps a portion of the side sill 2, though it will be understood that the door may equally well be hinged upon any transverse member of the underframe, as a cross bearer if desired. In the structure illustrated, an operating shaft 6 extends lengthwise through the cross bearers and is rotatably mounted in suitable bearings 7 fixed to said cross bearers near the center sills. The cross bearer 3 is formed of a single sheet of metal bent to form a U-shape, though the cross bearers of the car may be of any desired form which will provide spaced walls as 8 and 9 between which the principal mechanism of this invention may be disposed. Fixed to the shaft 6, between the walls 8 and 9, are a pair of chain wheels as 10 and 11, the wheel 10 being somewhat smaller in diameter than the wheel 11. An idler wheel 12 is supported in a suitable bracket 13, between the walls 8 and 9, at a point relatively near the outer side of the car and in a horizontal plane above the operating shaft. The idler 12 may as well be supported on a pin 12^a passing through the contiguous diaphragms 8 and 9 if desired as shown in Fig. 3 thus dispensing with the bracket 13. Chain 14 extends from the lug 15 on the periphery of wheel 10 to the lifting bar 18, being securely fastened at each end. Chain 14^a extends from the bar 18 around the idler 12 thence around the larger wheel 11 and to the lug 16 on the periphery of the wheel 11 whence it is secured. Coincident irregular slots 17 are formed in each of the walls 8 and 9, and the lifting bar 18 is extended through said slots, bridging the space between the walls, and extending beyond the outer faces of said walls. Each of the opposite projecting ends of the lifting bar 18 is connected to a lifting link as 19, which links extend into pivotal engagement with the doors 4 as best seen in Fig. 2. Suitable castings

17^a—17^a are fixed to the walls 8 and 9 for reinforcing said walls and for providing a relatively broad bearing surface for the lifting bar 18. The chains 14 and 14^a are pivotally connected as at 21 to the intermediate portion of the lifting bar for moving said bar bodily along the slot 17. The slot 17 is arranged with upper and lower horizontal portions and an intermediate oblique portion inclined slightly, toward the outer side of the car, at its upper end. The lower portion of the slot is extended toward the center sill, the extreme end thereof serving as an abutment against which the lifting bar 18 is adapted to rest for supporting the door in open position. The upper portion of the slot is extended away from the oblique portion and the bottom wall thereof serves as a positive support for the lifting bar 18 when the doors are in closed position, thus serving as a support for the doors through the links 19 for locking the doors in such position.

It will be observed that when the door is closed and locked and the lifting bar 18 is in engagement with the bottom wall of the horizontal portion at the upper end of the slot 17, said lifting bar is substantially in the plane of a line drawn tangent to the under sides of the chain wheels 10 and 11 and the idler 12 so that the chain 14, connected to said lifting bar is extended practically in a straight line from the periphery of the wheel 10 to the periphery of the idler 12, but when the door is open, the lifting bar 18 is considerably below the plane of such a line so that the chain 14 can no longer extend in a continuous straight line but is dipped or bent downwardly necessitating a somewhat greater free length of chain from the pulley 11 over idler 12 to the bar 18 than when the lifting bar is in locking position. In order to effect such a variation of the relative length of the free portion of the chain, one of its end portions is wound approximately one revolution on the large chain wheel 11. As the lifting bar moves downwardly along the slot 17, away from the straight line referred to, the chain 14^a, unwinding from the larger wheel 11, produces a lengthening of the free portion of the chain, which term "free portion" indicates that portion of the chain not directly engaged upon the chain wheel 11 or idler 12.

In operation: assuming the door to be open, as shown by dotted lines in Fig. 1, and the lifting bar 18 to be in position engaging the lower end of the slot 17 and supporting said door, rotation of the operating shaft 6 in a contra-clockwise direction (Fig. 1) will draw upon the upper lead of the chain and through the idler 12, will draw the lifting bar first along the lower horizontally disposed portion of the slot, thence

upwardly along the oblique portion of said slot and finally force it into locking position in the horizontal portion at the upper end of said slot, when the door will be positively locked and the thrust thereof transmitted through the links 19—19 and lifting bar directly to the cross bearers. In opening the door, rotation of the operating shaft will draw on the lower lead of the chain 14 and pull the lifting bar into the oblique portion of the slot, continued rotation of the operating shaft permitting the door to fall by gravity to its open position, where the bar 18 will rest in the inner end of the bottom horizontal portion of said slot and be supported thereby.

What I claim is:

1. In a door operating device, the combination comprising a car frame, a door, an operating shaft, a guide formed on said car frame, a lifting link, one end of which engages said door said link being adapted to travel on said guide, a pair of chain wheels fixed to said operating shaft, and a chain engaging said wheels and being connected for moving said lifting link.

2. In a door operating device, the combination comprising a car frame, a door, an operating shaft, a guide formed on said car frame, a lifting link engaging said door, and adapted to be directed by said guide, a pair of chain wheels fixed to said operating shaft, a chain fixed by one of its ends to one of said wheels and having its other end wound upon and fixed to the other of said wheels.

3. In a door operating device, the combination comprising a car frame, a door, an operating shaft, a guide formed on said car frame, a lifting link engaging said door, and adapted to be directed by said guide, a pair of chain wheels fixed to said operating shaft, a chain fixed by one of its ends to one of said wheels and having its other end wound upon and fixed to the other of said wheels, said chain being connected intermediate its ends for moving said lifting link along said guide.

4. In a door operating device, the combination comprising a car frame, a door, an operating shaft, a guide formed on said car frame, a lifting link engaging said door and having one of its ends adapted to be directed by said guide, a pair of chain wheels of different diameters fixed to said operating shaft, a chain fixed by one of its ends to the smaller of said wheels and having its other end fixed to the larger of said wheels and being connected intermediate its ends for moving said lifting link along said guide.

5. In a door operating device, the combination comprising a car frame, a door, an operating shaft, a guide formed on said car frame, a lifting link engaging said door and

- having one of its ends adapted to be directed by said guide, a pair of chain wheels fixed to said operating shaft, a chain fixed by one of its ends to one of said wheels and having 5 its other end fixed to the other of said wheels and being connected intermediate its ends for moving said lifting link along said guide, and an idler wheel for said chain, a part of said guide being removed from the 10 path of said chain when the door is in closed position and means for providing additional free length of chain as said lifting link is moved toward one end of said guide.
6. In a door operating device, the combination comprising a car frame, a door, an 15 operating shaft, a guide formed on said car frame, a lifting link engaging said door and having one of its ends adapted to be directed by said guide, a pair of chain wheels fixed 20 to said operating shaft, a chain fixed by one of its ends to one of said wheels and having its other end wound upon and fixed to the other of said wheels and being connected intermediate its ends for moving said 25 lifting link along said guide, an idler wheel for said chain, one end of said guide being removed from a direct line extending between said chain wheels and said idler.
7. In a door operating device, the combination comprising a car frame, a door, an 30 operating shaft, a guide formed on said car frame, a lifting link engaging said door and having one of its ends adapted to be directed by said guide, a pair of chain wheels fixed 35 to said operating shaft, a chain fixed by one of its ends to one of said wheels and having its other end wound upon and fixed to the other of said wheels and being connected intermediate its ends for moving said lifting 40 link along said guide, an idler wheel for said chain, one end of said guide being removed from a direct line extending between said chain wheels and said idler, and said chain wheels being adapted to provide additional 45 free length of chain as said lifting link is moved toward the removed end of said guide.
8. In a door operating device, the combination comprising a car frame, a door, an 50 operating shaft, a guide formed on said car frame, a lifting link engaging said door and having one of its ends adapted to be directed by said guide, a pair of chain wheels fixed to said operating shaft, a chain 55 engaging said wheels and being connected for moving said lifting link, an idler wheel for said chain, one end of said guide being removed from the path of a direct line between said chain wheels and said idler, and 60 said chain wheels being adapted to vary the free length of said chain as said lifting link is moved along said guide.
9. In a door operating device, the combination with a car frame comprising a cross 65 bearer, of a pair of dumping doors disposed upon opposite sides of said cross bearer, means extending through said cross bearer and linked to said doors, and mechanism within said cross bearer engaging said last mentioned means for operating said doors.
10. In a door operating device, the combination with a car frame comprising a cross bearer, of a pair of dumping doors disposed 70 upon opposite sides of said cross bearer, means extending through said cross bearer and linked to said doors, and chain operated mechanism within said cross bearer engaging said last mentioned means for operating said doors.
11. In a door operating device, the combination comprising a car frame, a door, an operating shaft, a guide formed on said frame, a lifting link having its opposite ends 75 engaging said door and guide, a pair of chain wheels on said shaft, and a chain operable thereby, said chain being connected with said link.
12. In a door operating device, the combination comprising a car frame, a door, 80 a shaft mounted in fixed position, and an idler, both below said door, locking means for said door and a chain controlled by said shaft and idler adapted to control said locking means.
13. In a flush bottom car, the combination comprising a door, an operating shaft mounted in fixed position, a fixed idler, a member having an angled slot therein extending relatively between said shaft and 85 said idler and chain operated means guided by said slotted member adapted to close said door.
14. In a flush bottom car, a door operating mechanism comprising doors, an operating shaft, supports for the doors connected thereto and with said shaft and a shaft support provided with a relatively Z-shaped slot formed therein.
15. In a flush bottom car, a door operating mechanism comprising doors, an operating shaft, a shaft support provided with a relatively Z-shaped slot formed therein, means 90 slidably in said slot and door supporting links connecting said slidably means and said doors.
16. In a flush bottom car, a door operating mechanism comprising doors, an operating shaft, a shaft support provided with a relatively Z-shaped slot formed therein, a bar 95 slidably in said slot and means connecting said doors and said bar.
17. In a flush bottom car, a door operating mechanism comprising doors, an operating shaft, a shaft support provided with a relatively Z-shaped slot formed therein, said support comprising spaced members, door lifting means operable between said spaced 100 members.

members and means connecting said lifting means and said doors.

18. In a flush-bottom car, the combination with a drop bottom door and a support therefor, of an operating shaft mounted in fixed position, a member supporting said shaft and provided with an angled slot therein, a portion of which slot is inclined, a door lifting bar adapted to be guided by said slot and actuated by said shaft, and a link connected to the bar and to said door.

19. In a car, the combination comprising a door adapted to be lifted to a horizontal position, an operating shaft, means for lifting said door, including a pivoted member depending from said door adapted to support the same in closed position and a member having a slot including a horizontal and

an inclined portion adapted to serve as a guide for said pivoted member.

20. In a dumping car, a slotted cross-bearer, a lifting bar extending through and movable longitudinally of the slot in said cross-bearer, a shaft rotatable in fixed position, actuating means connecting said shaft and said lifting bar, doors, and links connecting said doors positively with said bar on opposite sides of the cross-bearer in the near vicinity of said cross-bearer.

In witness whereof I have hereunto set my hand in the presence of two witnesses.

DONALD S. BARROWS.
